UNITED STATES PATENT OFFICE

JACOB E. SCHADLE, OF ST. PAUL, MINNESOTA.

PNEUMATIC BRUSH.

No. 869,023.

Specification of Letters Patent.

Patented Oct. 22, 1907.

Application filed January 16, 1905. Serial No. 241,183.

To all whom it may concern:

Be it known that I, JACOB E. SCHADLE, a citizen of the United States, residing at St. Paul, in the county of Ramsey and State of Minnesota, have invented a new and useful Pneumatic Brush, of which the following is a specification.

My invention relates to improvements in pneumatic brushes, more particularly, though not exclusively, intended for use as blackboard-erasers.

10 It is the object of the invention to provide an efficient brush for use in connection with a system of disseminating pipes, subject to the influence of air-exhausting means, for example like those described in my application for Letters Patent filed June 20, 1904, 15 Serial No. 213,266.

In the use of the apparatus described and claimed in that application I have found that, because of the strong affinity of chalk dust for moisture, there is a tendency to clog the interior of the brushes and other 20 parts of the apparatus with such dust. I have discovered that to obviate said objection it is desirable to use a pneumatic brush which is provided with a deflector adapted to prevent the packing of the dust in the interior of the brush structure. To that end, and to produce a more serviceable pneumatic brush for general uses, my invention consists of the elements illustrated in the accompanying drawing, and hereinafter described and claimed.

25 In the said drawing—Figure 1 is a central sectional view, and Fig. 2 is a bottom plan view of the casing with the brush removed.

Referring to the said drawing, the reference letter A designates the brush or eraser proper; B its casing; C the deflector; D a valve for establishing and cutting 30 off communication between the hollow casing and the disseminating system; and E a push button accessible from outside the hollow casing controlling said valve.

The brush A and its back 3 are preferably circular in horizontal section. The brush comprises cleaning 40 elements such as tufts 1, confined by ferrules 2 and fastened into the brush back 3 by the usual means employed for that purpose in the art of brush making. The brush back 3 is provided with an opening 4 extending through said back from the exterior of the 45 brush structure into the interior of the hollow casing. This casing is formed by fastening a cap 5 to the brush back 3. As illustrated in the drawings, this fastening is accomplished by screws 6.

The deflector C is arranged within the hollow casing 50 B and is preferably of an agitator type, as shown, consisting of a small air fan pivotally connected with the shaft 7 said shaft being attached to the interior of the cap 5 at the point 8. The deflector is adapted to re-

55 move freely when communication is established between the pipe 9 of the disseminating system and the interior of the hollow casing, and a partial vacuum is established within said casing by any suitable means (not shown); the said pipe 9 being, of course, connected with a system of tubing running to the air exhaust producing means, for example, like the system of tubing and fan described in my aforesaid application for Letters Patent. The hollow casing is hermetically connected to the brush back, the only opening into the interior being through the back 3 and the valve-controlled passage leading to the pipe 9. The communication between the disseminating system and the interior of the hollow casing is made at will, by pressing the button attached to the hollow casing, and which thrusts upon the pivoted lever 11 attached to the valve D. When the pressure of the hand upon the button E is removed, the latter is returned to its former position, and the valve is closed by means of the spring 12.

In operation, while the valve is open, a partial vacuum is created within the hollow casing by means of the air-exhaust system; air is drawn through the opening 4 and a current of air is thus established, which causes the deflector C to rotate, and draws the dust removed by the brush in the usual manner, into the hollow casing and thence out through the pipe 9. The rotation 80 of the deflector agitates the cloud of chalk or other dust in the casing and prevents packing and clogging of the interior of the casing and disseminating system.

When not in use, the hand being removed from the button, communication with the disseminating system is closed by the valve D; the suction is cut off and the energy required to produce the vacuum is saved.

Having thus described my invention, what I claim as new and desire to secure by Letters Patent is:

1. The combination of a brush, the back whereof is perforated, a hollow cap removably attached to said back to provide a chamber, a deflector journaled in the cap within said chamber and located above said perforation, a conduit connecting said chamber to an air-exhaust system, and a valve in the chamber for regulating said air exhaust. 90
2. In a dust remover, the combination of a brush having a perforated back, a cap provided with a chamber, said brush back adapted to be removably attached to said cap whereby to close the chamber, a rotary depending deflector journaled in the cap within said chamber, and a conduit communicating with said chamber, and a valve at the point of communication. 95
3. In a dust remover, the combination of a brush having a perforated back, a cap provided with a chamber, said brush back adapted to be removably attached to said cap whereby to close the chamber, a rotary depending deflector journaled in the cap within said chamber, and a conduit communicating with said chamber, and a valve positioned immediately over the perforation, an exhaust conduit communicating with said chamber, and a valve at the point of communication. 100

In testimony whereof I have signed my name to this specification, in the presence of two subscribing witnesses:

JACOB E. SCHADLE.
